(57) **CLAIM**

The ornamental design for a blood observation device, as shown and described.

DESCRIPTION

FIG. 1 is a front perspective view of a blood observation device.

FIG. 2 is a rear perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof.

FIG. 8 is a right side elevation view thereof.

FIG. 9 is a front perspective view thereof with the cover open; and,

FIG. 10 is a rear perspective view thereof with the cover open.

The broken lines shown in the drawings illustrate portions of the blood observation device that form no part of the claimed design.
